UNITED STATES PATENT OFFICE

160,931

DOCUMENT PHOTOGRAPHING MACHINE

William W. Eaton, Milford, Conn., and Harold T. Olson, Baldwin, N. Y., assignors to Remington Rand Inc., New York, N. Y., a corporation of Delaware

Application October 4, 1949, Serial No. 5,287

Term of patent 7 years

(Cl. D64—11)

To all whom it may concern:

Be it known that William W. Eaton, a citizen of the United States, residing at Milford, in the county of New Haven and State of Connecticut, and Harold T. Olson, a citizen of the United States, residing at Baldwin, in the county of Nassau and State of New York, have invented a new, original, and ornamental Design for Document Photographing Machine, of which the following is a specification, reference being made to the accompanying drawing, forming a part thereof.

Fig. 1 is a perspective view looking at the front of the document photographing machine, showing the new design.

Fig. 2 is a side elevation of the right-hand side of the machine.

Fig. 3 is a side elevation of the left-hand side of the machine, and

Fig. 4 is a rear elevation thereof.
The invention claimed is:
The ornamental design for a document photographing machine, as shown.

WILLIAM W. EATON.
HAROLD T. OLSON.
